SIGN WITH INTERCHANGEABLE
CHARACTERS

Tom J. Bennett, Oklahoma City, Okla.

Application October 14, 1949, Serial No. 121,314

1. Claim. (Cl. 40—140)

1.

My invention relates to signs, such as are suitable for display along roadways, streets and highways, and are required to be visible to motorists at night. The invention is applicable to house number signs, particularly curb signs, street signs, highway signs and markers and the like. In my copending Patent No. 2,515,818 of July 18, 1950, I disclosed a sign suitable for house number signs to be planted in the lawn or along the curb. The sign of the present invention is in certain respects an improvement upon the sign of said application.

The chief object of the present invention is to provide an improved sign on which the indicia may be easily and quickly applied, and as easily changed without impairing the light reflecting character of the indicia and the legibility thereof.

A further object is to provide a new indicia unit or sign character, such as a numeral or letter suitable to be applied to or removed from the body of the sign by hand.

A further object is the provision of a new method of mounting active light reflecting material upon a suitable background for making up the novel indicia above referred to.

In the signs I originally put out under the aforesaid application, I prepared numerals by mounting "scotch light" fabric on a backing sheet of paper cardboard or the like, and cutting out the desired numerals. These numerals were carefully registered on the plate, pressed flat against the plate and cemented thereto. I know that it is old to mount detachable numerals and letters onto a mounting board, but I observed that signs employing such characters generally look rough and uneven in daylight and were illegible by reflected light at night. This I ascertained generally comes from the fact that the bodies of the letters or numerals are not registered in the same plane, and also the bodies of the letters warp or are bent out of a plane, and hence they reflect light cast upon them in various directions due to such bent or warped conditions. Hence, they are frequently illegible at the distance at which they must be read. That is to say, even if the bodies of such letters or numerals were accurately flat in optically perfect planes, like the surface of plate glass, mounting them by hand upon a background by readily attachable and detachable means would have the effect of establishing those planes of the individual letters tilted slightly relative to each other in various directions and reflected light, as from the headlights of an automobile, would

be cast in various directions, and some of the letters might be visible and some would not be visible at all.

Likewise, if the body of the letters or numerals should be warped or bent out of a strict optical plane, reflected light from one part of the body would be cast in one direction and another part in another direction, with the overall result that the reflected image of the letter would appear to the observer to be mutilated and the letter would be illegible.

I observed that the flat numerals which I applied to the board or body of my early form of sign had the property of reflecting back light cast upon the same, through a fairly wide angle. The said numerals covered with the minute colored glass beads give about the same reflection from various viewpoints, i. e., the observer and light source being anywhere within a wide angle of a line normal to the plane of the sign. That is to say, assume you are sitting in an automobile with headlights shining straight ahead, and assume the headlights strike a flat surface covered with this colored glass bead material. It is not necessary that the plane of the surface so treated be presented squarely to the light and to the eye of the observer for the sign to be plainly visible. The sign may be standing at quite an angle to the incident light, yet a strong light is reflected back to the eye of the observer in a line fairly close to the line of incident light.

From this I drew the conclusion that the numerals or letters coated with this material would not need to lie in a flat plane, but could be somewhat warped or even offset without casting shadows by variations in the reflecting index due to such departure from a predetermined plane.

Now it is highly desirable that a curb sign (bearing house numerals or the like) carry the same indicia on the front and on the back, so that a person approaching the number from either direction can read the sign. This is particularly desirable at night. Where the numerals are glued or stuck on the plate, this presents no particular problem, but for a sign in which the numerals are to be applied to the field, i. e., at the location of the sale, the problem of attaching the same set of numerals in reverse order and doing it neatly presents a serious problem.

However, I found that the same quality above described, and which made the numerals legible even though somewhat warped or bent out of a plane, made it possible to clinch the tab of the

front number over the face of the back number, or vice versa, without impairing the effectiveness or legibility of the sign. In other words, the clinching of the tabs of one number over the face of the number on the opposite side left a tab surface offset from the plane of the number over which it was clinched, and also usually not exactly parallel to the plane of the overlapped numeral.

Furthermore, the numerals could be removed from an unwanted sign and be used in making up another numeral combination without impairing the light reflecting character of the tabs or of the bodies of the numerals.

Now in order to acquaint those skilled in the art with the manner of constructing and operating a device embodying my invention, I shall describe, in connection with the accompanying drawing in which like reference numerals indicate like parts, the preferred embodiment of the same.

In the drawings:

Figure 1 is a front elevational view of a sign embodying my invention;

Figure 2 is a transverse section of the same taken on the line 2, 2 of Figure 1;

Figure 3 is a fragmentary back elevational view of that portion of the sign illustrated in Figure 1 immediately above Figure 3;

Figure 4 is an elevational view of an individual numeral showing the attaching tabs;

Figure 5 is a diagram of the mechanism for applying the light reflecting coating to the aluminum sheet; and

Figure 6 is an enlarged fragmentary section of the light reflecting beadlike particles adhesively bonded to the surface of the metal backing.

The preferred form of the invention, as shown in Figures 1 to 4, inclusive, involves three main structural parts, namely, the inverted generally U-shaped frame 1, the plate 2, and the detachable numerals 3.

The frame 1 consists, in general, of a piece of rod stock bent into the form of an open rectangular frame with a horizontal upper portion and rounded corners leading to two vertical portions, the lower ends of which constitute legs 4, 4 adapted to be thrust or projected into the ground or mounted in a suitable support or supports for holding the sign. This frame may be made of iron or where, from the nature of the soil, corrosion might be excessive, the frame may be made of a stainless steel rod. As disclosed in my prior copending application, the frame may be made partly of tubular stock with legs of solid rod stock.

The plate 2 is made of sheet metal and in the specific example herein illustrated, this may be aluminum sheet, semi-hard, .025 in thickness. The frame and plate are preferably given a coating of black paint or enamel, or they may otherwise be coated and preferably brought to a dark neutral color. Aluminum is used to avoid rust.

A row of seven horizontal slots 5, 5, about $\frac{1}{8}''$ x $\frac{3}{8}''$ and about $1\frac{1}{4}''$ apart on centers, are punched in the plate 2 near the upper margin of the same, and a similar row of seven slots 6, 6, 6 registering vertically with the slots 5, 5, 5 is punched in the sheet adjacent the lower margin. The rows may be approximately $2\frac{3}{4}''$ apart on a plate face of approximately $5\frac{1}{4}''$ x $10\frac{1}{2}''$.

The upper corners of the sheet are cut off, and the edges of the sheet at top and side are curled over the frame 1 to produce the curled edges 7, 8 at top and sides, respectively. The sign char-

acters, which in this case are numerals, are made of dead soft aluminum sheets, approximately .016" in thickness, and are coated on their exposed or outer faces, including the integral mounting tabs, with a light-reflecting material, consisting essentially of small beadlike particles of glass. Obviously, letters or other indicia may be employed. The dimensions given for a numeral sign are by way of example, and not by way of limitation. Letters and numerals may be employed, and the size and spacing suitable for the same may be utilized within my invention.

The outline of the numerals has been designed to make the sign as legible as possible when the characters are spaced according to the uniform spacing required by the slots 5, 6 in the plate 2. At Figure 4 I have shown, for example, the numeral 3, as consisting of the main body portion 10 and tabs 12, 12 integral with the body portion 10. The body portion 10 and the tabs are provided with a light reflecting surface consisting of a layer of minute glass beads or beadlike particles of glass, partly embedded in an elastic adhesive bonded to the surface of the numeral.

These numerals are adapted to be applied to the board or plate 2 with the bare hands only. It will be observed that in the preferred embodiment here described, by way of illustration, there are seven slots in each row, and that the numerals for a four place numeral are fastened in the first, third, fifth and seventh pair of holes. For a three-place number, the numerals would be located in the second, fourth and sixth holes. For a two-place number the numerals would be fastened in the third and fifth slots, and, obviously, if a one-place number were to be mounted on the sign, the single numeral would be attached in the fourth slot.

This holds true for both front and back. Hence, in the example herein illustrated, employing the number 1034, to have the sign read the same on each side, it is necessary that the numeral 4 be on the side opposite the numeral 1 shown in Figure 1; that the numeral 3 be on the other side of the numeral 0 of Figure 1; that the numeral 0 be on the opposite side of the numeral 3 shown in Figure 1, and that the numeral 1 be on the opposite side of the numeral 4 shown in Figure 1. Figure 1 shows the side of the sign in which the edges of the plate 2 have been curled over, and, hence, may be regarded as the backside of the sign. That is because in the preferred form of the sign the plate 2 lies in a plane tangent to one side of the frame. Obviously, the plate could be held in the plane of the frame.

As shown in section in Figure 2, the numerals are first applied to the backside of the sign by bending the tabs 12, 12 at substantially right angles to the body 10, and inserting the same through the slots 5, 6 at top and bottom, and then clinching them over as indicated at 13, 13 in Figure 2.

After the numerals have been applied to the backside of the sign and their tabs clinched over the edges of the plate, the corresponding numerals in the proper order are attached by means of their tabs extended through the same slots and clinched over the adjacent face of the sign numeral on the backside as indicated at 14, 14 in Figures 1 and 2. By this application of the numerals to the plate, the tabs of the numbers applied on the back of the plate 2 do not show on the front, since they are concealed by the bodies of the numerals on the front of the plate 2, but

the tabs of the numerals on the front of the plate 2 are clinched over, and show on the face of the bodies of the numerals on the back of the plate 2. This does not substantially detract from the light reflecting ability of the overlapped numerals.

The light reflecting surface which is applied to the face of the numerals and their tabs, as shown on an enlarged scale in Figure 6, consists of a great number of minute beadlike colored glass particles 15, partly embedded in a layer 16 of an elastic adhesive which is mounted upon the metal 17 of the sign character. The preferred color is green. There are various ways of producing this bead-covered surface, as, for example, the metal 17 may be coated with the elastic adhesive layer 16 and the glass beads thereupon applied to the same and partly embedded and bound by the said adhesive 16. The adhesive may be set by drying out a solvent, or by baking the same, or in other ways familiar to those skilled in the art.

An advantageous way of applying the light reflecting coating to the surface of the numerals is illustrated in Figure 5. There is found on the market a material known as "scotch light" fabric, manufactured by Minnesota Mining & Manufacturing Company, consisting of a sheet of plastic material, coated on one side with beadlike particles of glass embedded therein. This material may be secured in strips, and rolled up in a roll as indicated at 18 in Figure 5. The backside of the sheet which does not have any of the glass beads thereupon, but which consists solely of the adhesive material 16, is rendered tacky by spraying the same as indicated at 19 with a solvent by means of a spray nozzle 20 or the like. The sheet 22, rendered sticky by the application of the solvent spray, is carried forward a sufficient distance to insure the effectiveness of the solvent upon the surface of the sheet 22, and then the sheet 22 and a corresponding strip of aluminum sheet 17 are passed between the elastic rollers 23, 23 to produce the composite sheet 24, which consists of the dead soft metallic backing 17, the layer of adhesive 16, and the beadlike particles of glass 15, as shown in section in Figure 6. The individual numerals may then be cut out by a punch and die, or by a strip die, as may be desired. It is desirable, in the interest of good workmanship and minimum of space, to have the numeral and its integral ears or tabs perfectly flat when coming from the cutting die, but it is not essential that it be so, because of the unique property of the reflecting surface to act throughout a wide angle of incidence.

The peculiar property of this light-reflecting surface is explained in the fact that the surface is composed of minute spheres of glass, and the light entering at any point on a sphere is most strongly reflected back in the direction of entry, by internal reflection.

The mode of use, as heretofore explained, is such as to permit of a highly effective method of distribution and sales. The body of the sign, comprising the frame and plate, is fabricated and assembled, and a stock of the numerals made of dead soft metal, such as aluminum coated with the beadlike particles of glass by means of an adhesive layer of flexible character, is suitably manufactured and stocked. Aluminum is preferred because it is inexpensive and does not stain the surface of the sign.

In the foregoing specification, I have given certain dimensions by way of example, and have in-

dicated the materials of which the various parts may be made. These specific instructions are not to be taken as limiting, but as illustrative, and to apprise those skilled in the art of the required characteristics of the various parts or operations.

The salesman loads up a stock of sign bodies, and a stock of assorted numerals in the flat, and goes along a street, either making up the signs with the appropriate numerals as he goes along; or making them up, if he so wishes, at the beginning of his campaign on a particular street. Usually, he will make them up as he goes along; for this obviates the necessity for preliminary scouting and determining what numbers are required, and what numbers are not required. To make up a sign, he takes two sets of the appropriate numerals, to make up a house number; as, for example, No. 1034, as herein illustrated; and he applies the numerals left to right, first, on the back side of the sign plate, that is, the side illustrated in Figure 1, extending the tabs through the slots 5, 6, and clinches them over with the fingers on the front of the plate 2. Then he takes the other set of numerals 1034, and reading from left to right on the other side, he extends the tabs or ears through the slots 5, 6, and clinches them over on the back side over the body of the numerals previously placed, and the sign is ready for placement and use.

He then plants the signs at an advantageous location in the parkway along the curb, or wherever the sign is required, and preferably leaves it, first obtaining the consent of the householder to the procedure, and with the assurance that the householder is not obligated to pay for the sign if he does not wish it, after seeing its effectiveness at night. A day or two later the salesman goes along the street, and asks the householders to purchase the signs which have been placed, and a surprisingly large percentage of householders do so. However, in case of "no sale," the sign is taken up, the tabs on the back are quickly unclinched to remove the numerals on the front, and then the tabs which have thus been revealed are unclinched, and the numerals are taken off the back. The tabs may be straightened out and the numerals put back into stock, and may be used over again, with full effectiveness.

It will be apparent from inspection of Figure 2 that the soft metal numerals will very probably be slightly bent or warped by manipulation in fastening the numerals upon the plate 2, but this is immaterial, and is not noticeable, either in daylight or under artificial light, as when the numeral reflects the light from the headlights of an automobile.

The unique utility of this invention has made it possible for great numbers of the public to have effective signs readily legible to those seeking the location of a particularly numbered house or establishment.

The use of this invention in highway signs and markers is obvious.

65 I claim:

In a sign, the combination of a mounting plate having upper and lower mounting edges adapted to be disposed substantially horizontally, a pair of legible sign characters each comprising a metal body formed of thin dead soft aluminum of substantially uniform thickness throughout, said body having integral extensions at top and bottom in the form of bendable tabs, said body including said tabs having the front face thereof covered with a coating of elastic adhesive bonded

to said face, and a layer of light reflecting bead-like glass particles adhering to and covering the outer surface of the adhesive, said adhesive and particles providing a light reflecting coating over the surface of the body including said tabs, one of said characters lying against the front of the plate and having the tabs clinched over the mounting edges of the plate, the other of said characters lying on the back of the plate and covering the clinched tabs of the first character, the tabs of the second character being clinched over the tabs of the first character and extending over the adjacent top and bottom margins of the face of the first character, the light reflecting ability of said coating being substantially unaffected by the warping and bending of the body out of a single plane incidental to bending of the tabs in mounting the body on said supporting plate, the

5

10

elastic adhesive coating with beadlike surface layer being capable of conforming to the bending of the body and the tabs while retaining the beadlike layer substantially intact.

TOM J. BENNETT.
